(57) **CLAIM**

The ornamental design for a cab, as shown and described.

DESCRIPTION

FIG. 1 is a perspective view of a cab showing our new design;

FIG. 2 is a front view thereof;

FIG. 3 is a rear view thereof;

FIG. 4 is a right side view, the left side view being a mirror image thereof;

FIG. 5 is a top view thereof; and,

FIG. 6 is a bottom view thereof.

The oblique surface shading represents transparency.

The broken lines illustrate structure or features that form no part of the claimed design.
